UNITED STATES PATENT OFFICE.

MARTIN LOGAN, OF NEW YORK, N. Y.

DESIGN FOR A RUBBER CUSHION FOR HORSESHOES.

SPECIFICATION forming part of Design No. 33,790, dated December 25, 1900.

Application filed November 24, 1900. Serial No. 37,693. Term of patent 14 years.

To all whom it may concern:

Be it known that I, MARTIN LOGAN, a citizen of the United States, residing at New York, in the county of New York and State of New York, have invented and produced a new and original Design for a Rubber Cushion for Horseshoes, of which the following is a specification, reference being had to the accompanying drawings, forming part thereof.

- o Figure 1 is a plan view of a rubber cushion for horseshoes, showing my new design. Fig. 2 is a sectional view taken on the line 2 2 of Fig. 1, and Fig. 3 is a sectional view taken on the line 3 3 of Fig. 1.
- 5 As shown in the drawings, the leading or material feature of my design consists of a cavity or depression in the central portion of the cushion, the wall of said cavity being fluted or corrugated, and depressions on both
- o sides of said central depression, and in which side depressions are conical-shaped nipples, their outer surfaces being also fluted or corrugated, and the apices of said nipples being in the plane of the upper or outer surface of

the cushion, the walls of said side depressions 25 being also corrugated, as shown.

Referring to the drawings, the cushion has the outline or contour as shown, A representing the upper or outer surface of said cushion, and B the cavity or depression in the 30 central field thereof, the wall of said depression being corrugated, as indicated at C.

D D represent the side depressions, whose walls are corrugated, as represented at E, and from the bottom of said depressions rise 35 the corrugated or fluted nipples F, their apices lying in the plane of the upper surface A of the cushion, as indicated in Fig. 2.

Having described my invention, what I claim as new, and desire to secure by Letters 40 Patent, is—

The design for a rubber cushion for horseshoes, as herein shown and described.

MARTIN LOGAN.
